UNITED STATES PATENT OFFICE.

WILLIAM C. JORDAN, OF MADISON, NEW JERSEY, ASSIGNOR TO BELL TELEPHONE LABORATORIES, INCORPORATED, OF NEW YORK, N. Y., A CORPORATION OF NEW YORK.

TELEPHONE-EXCHANGE SYSTEM.

Application filed February 8, 1927. Serial No. 166,637.

- This invention relates to telephone systems and has for its object the provision of means for establishing connections with telephone subscribers whose substation equipment is located at a point remote from the central office. It is sometimes desirable for telephone subscribers, whose place of business is located in a small town, to have direct telephonic connection with some larger and better known city; or an urban business subscriber may wish direct telephonic connection with the suburbs. Where the central office is equipped with automatic switching apparatus and the interconnecting lines are of great length, the establishment of connections may not be satisfactorily accomplished by the automatic apparatus if the lines are of the standard type. A line circuit arrangement of a special type is therefore necessary for such subscribers, which will permit the completion of connections therewith under the control of an operator at the central office.
- In accordance with the present invention an intercepting line is provided at the central office, individual to each line extending to a distant subscriber's substation. On outgoing calls the switching apparatus of the central office selects this intercepting line and an operator connects it with the subscriber's line. If a call is initiated over a trunk by the subscriber when the corresponding intercepting line has been seized by the switching apparatus, a distinctive signal is displayed before the operator. The intercepting line is also arranged so that when the operator is signaled therewith, the signal may only be retired by the act of the operator in signalling the called subscriber.
- The preferred embodiment of the present invention, specifically stated, consists of a two-way line extending from a jack at an "A" operator's position of a machine switching central office to a distant private branch exchange, and a one-way intercepting line which is individual to the first line and which extends from the bank terminals of the automatic switches of the machine switching central office, to an intercepting
- jack at the position. The two-way line is provided with a repeating coil, a line lamp, and equipment controllable over the line by means of ringing current from the branch exchange to operate the line lamp and a disconnect signal in the operator's cord circuit, as well as ringing equipment controllable by the operator to signal the branch exchange. The intercepting line has equipment responsive to ringing current supplied by the switching apparatus to control a calling lamp. In addition there is provided a key by means of which the operator may cause the call to be charged. In the case of calls incoming from the machine switching equipment, the operator responds to the calling lamp associated with the intercepting line to connect the intercepting jack with the line jack by a cord circuit. She then signals the branch exchange over the two way line. On calls incoming from the branch exchange the operator inserts the answering plug of her cord circuit in the line jack and employs the calling plug to extend the desired connection by means of trunk lines appearing at her position. If a call is originated at the branch exchange after the intercepting line has been seized by the switching apparatus, the line lamp will be caused to flash whereupon the operator will inform the subscriber that the line has been taken for an incoming call. Where an incoming call is controlled by a distant operator and that operator rings over the connection, a lamp associated with the cord circuit employed in completing the connection will be lighted until extinguished by the operation of the ringing key to resignal the branch exchange.
- The manner in which the apparatus embodying the invention functions will be more clearly understood from a consideration of the following description in connection with the accompanying drawings in which:
- Fig. 1 shows a calling substation and an operator's position at a manual office equipped with key indicator apparatus, indicated by the dotted rectangle at the right of the figure;
- Fig. 2 shows an incoming selector at a machine switching office adapted for ex-

tending connections from key indicator equipment;

Fig. 3 shows a final selector;

Fig. 4 shows a cord circuit for use at an 5 "A" operator's position in a machine switching office;

Fig. 5 shows the line circuit for use between machine switching equipment and a remote branch exchange; and

10 Fig. 6 shows the method of arranging Figs. 1 to 5 inclusive.

Connection to branch exchange.

The establishment of a connection from a 15 subscriber in a manual office to the remote branch exchange will first be described. When the subscriber at manual substation 100 removes his receiver from the switch-hook, he closes a circuit from battery through 20 the left winding of line relay 101, outer back contact of relay 102, over his line and substation equipment to the inner back contact of relay 102, right winding of relay 101 to ground. Relay 101 operates, lighting line 25 lamp 103 which is located before an operator at the central office. The operator, observing lamp 103, inserts plug 104 of cord circuit 105 in answering jack 106. A circuit is thereupon closed from battery through 30 cord lamp 107, resistance 108, sleeves of plug 104 and jack 106, winding of cut-off relay 102 to ground. Relay 102 operates in this circuit, opening the circuit of relay 101 and extinguishing lamp 103. At the same 35 time a circuit is closed from battery, lower left winding of repeating coil 109, winding of supervisory relay 110, rings of plug 104 and jack 106, over the subscriber's line, tips of jack 106 and plug 104, upper left 40 winding of repeating coil 109 to ground. The operation of relay 110 connects battery through resistance 111 to the circuit of relay 102 in shunt of lamp 107, thereby preventing the lighting of lamp 107. The operator will 45 then operate talking key 112, connecting her headset 113 to the cord circuit 105 so that she may talk with the calling subscriber.

Having learned from the subscriber that the wanted line is located in the machine 50 switching exchange, portions of which are shown in Figs. 2 to 5 inclusive, she will operate a key, individual to the office at which the wanted line terminates and forming a part of the key indicator equipment represented by the rectangle at the right of Fig. 1. The operation of this key will cause the selection of an idle trunk outgoing to the distant office and the indication of the number of the selected trunk on an indicator 55 before the operator. Assuming that trunk 114 is selected, which trunk terminates in jack 115, the operator inserts the calling plug 116 in jack 115 as soon as she receives the indication. A circuit is thereupon closed 60 from battery, through lamp 117, resistance 65

124, sleeves of plug 116 and jack 115, winding of relay 118 to ground. Relay 118 in operating prepares an operating circuit and a holding circuit for relay 119, which is operated from the key indicator equipment 70 when the selection of the called line has been completed. A circuit for supervisory relay 122 similar to that for relay 110 is prepared when plug 116 is inserted in jack 115 but is not completed until relay 119 is operated and 75 the called subscriber answers. Therefore lamp 117 remains lighted as an indication that the connection has not been completed. The key indicator equipment includes numerical keys at the operator's position and 80 a sender under the control of which the wanted line is selected. After recording the number of the wanted line and inserting plug 116 in jack 115 the operator may attend to other calls. For a complete description 85 of the operation of the key indicator equipment, reference is made to U. S. Patent 1,513,362, granted to L. M. Allen, October 28, 1924.

When the first digit of the wanted number has been registered on the key indicator sender, a fundamental circuit is established between the incoming selector at the machine switching office and the key indicator sender. This circuit may be traced in part 90 from battery, through the left winding of relay 201, lower left contact of sequence switch cam 202, upper left contact of cam 203 over conductor 204 of the interoffice trunk 114 to the key indicator equipment, 100 where it extends through the stepping relay of the associated sender, back to conductor 205 of the trunk, lower contacts of cam 206 to ground. Relay 201 operates, closing a locking circuit for itself extending from battery through its left winding, right contact of cam 207, left front contact of relay 201, 105 upper left contact of cam 202, to the fundamental circuit as above traced. Relay 201 also closes a circuit from ground at its right 110 front contact, upper left contact of cam 208, winding of sequence switch magnet 200 to battery. The sequence switch is advanced to position 2 in this circuit.

In position 2 the energizing circuit of 115 relay 201 is opened but the locking circuit remains closed. A circuit is therefore closed from battery, through up-drive magnet 209, lower right contact of cam 210, upper right contact of cam 211, to ground at the right front contact of relay 201. The incoming selector is moved upward under the control of magnet 209 in its brush selecting operation. During this upward movement 120 a circuit is closed intermittently from ground over the lower left and upper right contacts of cam 212, commutator brush 213, conducting segments of commutator strip 214, upper right contact of cam 202 to the fundamental circuit. This ground holds 125

relay 201 operated and shunts the stepping relay of the selector in the well known manner. When the stepping relay has been released a sufficient number of times to satisfy the condition set up by the selector, the fundamental circuit is opened in the selector and relay 201 released. The release of relay 201 closes a circuit from battery through the winding of magnet 200, upper 10 right contact of cam 203, to ground at the right back contact of relay 201. The sequence switch is advanced to position 3 in this circuit.

In positions 3 and 4 brush tripping magnet 215 is operated over the lower contacts of cam 216. In these positions likewise, relay 201 operates, causing the selector to make group selection and advancing the sequence switch to positions 4 and 5 in the 20 manner described for brush selection. The shunting circuit for the stepping relay extends at this time from ground to brush 217 as previously traced and thence over conducting segments of strip 218, and the upper right contact of cam 203 to the fundamental circuit.

In position 5 a test is made of the trunk extending to the first final selector of the group selected, on the terminals of which 30 the incoming selector rests at this time. Relay 201 is operated in a local circuit extending from battery, through the right winding of relay 201, upper contact of cam 219, right normal contact of relay 220, upper left and lower right contacts of cam 221 to ground. Relay 201 in operating advances sequence switch 200 to position 6. It also prepares a locking circuit for itself which may be traced from battery, through the left winding of relay 201, right contact of cam 207, left front contact of relay 201, upper contacts of cam 216 to sleeve brush 224. If the final selector trunk, on the terminals of which the brushes are resting, is busy, 40 ground will be connected to its sleeve terminal, as will be described hereinafter, and the above traced locking circuit will be completed. Therefore, relay 201 will be held operated in position 6 and will operate magnet 209 to cause the selector to hunt for an idle trunk. Relay 201 is held operated between trunk terminals by a circuit, extending from battery through its right winding, contacts of cam 225, commutator strip 226, 50 brush 227, right contacts of cam 211, right front contact of relay 201 to ground. This circuit also ensures the centering of the brushes on the trunk terminals. When an idle trunk is found and this circuit is opened, 60 relay 201 releases, opening the circuit of magnet 209 and bringing the selector to rest. It also advances sequence switch 200 to position 7. When relay 201 releases, a circuit is closed from brush 224, upper contacts of 65 cam 216, left back contact of relay 201, lower

contacts of cam 243 to ground, marking the final selector busy. As soon as the sequence switch reaches position 6½, a direct ground over the left contact of cam 216 is substituted for ground over the above traced 70 circuit.

In position 7 relay 201 is again operated, the circuit being traceable from battery through the left winding of relay 201, left contacts of cam 202, left contacts of cam 216 75 to ground. In operating, relay 201, closes a locking circuit for itself extending from battery through its left winding, right contact of cam 207, left front contact of relay 201, upper contact of cam 228, brush 223, conductor 301 of the final selector trunk, resistance 302, left contact of cam 303 to ground. Relay 201 also advances sequence switch 200 to position 8, in which position 80 relay 201 remains locked to the final selector. Sequence switch 200 remains in this position throughout final selections.

With sequence switch 200 in position 8, the fundamental circuit extends from battery, over the lower left and upper right contacts of cam 304, right winding of relay 305, lower left contact of cam 306, lower left contact of cam 307, conductor 308, brush 222, right contact of cam 229, conductor 204, and thence through the key indicator sender 90 back to conductor 205, left contact of cam 210, upper right contact of cam 211 to ground at the right front contact of relay 201. Relay 305 operates in this circuit and closes a locking circuit for itself from battery over the lower left and upper right contacts of cam 304, right winding of relay 305, right contacts of cam 309, right front contact of relay 305, upper left contact of 95 cam 306 to the fundamental circuit as traced.

Relay 305 in operating closes a circuit from battery through the left winding of relay 310, right contact of cam 311, left front contact of relay 305 to ground at the right contact of cam 312. Relay 310 operates in 100 this circuit, closing a locking circuit for itself from battery through its left winding, lower contact of cam 311, back contact of relay 313, right contact of cam 314, outer front contact of relay 310, sleeve conductor 105 315, brush 224, upper right and lower left contacts of cam 216 to ground. This circuit is effective until sequence switch 300 leaves position 10, but is, of course, dependent on relay 313. Relay 310 also closes a circuit from battery through the winding of sequence switch magnet 300, right contacts of cam 316, inner front contact of relay 310 to ground, advancing the sequence switch to 110 position 2.

In position 2 a circuit is closed from battery through the winding of high speed up-drive magnet 317, lower right and upper left contacts of cam 318, left front contact of relay 305, to ground at the right contact 115 120 125 130

- of cam 312. At the same time a circuit is prepared from ground, over the lower contact of cam 303, commutator brush 319, commutator strip 320, upper right contact of cam 307 to the fundamental circuit. As the final selector is moved upward under the control of magnet 317, this circuit is intermittently completed to release the sender stepping relay in the well known manner.
- When the selector is in position to trip the proper set of brushes, relay 305 releases, releasing magnet 317 and bringing the selector to rest. A circuit is thereupon closed from battery, through the winding of sequence switch magnet 300, lower contact of cam 321, left back contact of relay 305 to ground at the right contact of cam 312, advancing the sequence switch to position 3.
- In positions 3 to 5 inclusive, the trip magnet 322 is operated over the upper right contact of cam 303. In position 3 relay 305 is reoperated and locked, advancing the sequence switch 300 to position 4 in a circuit from battery, through magnet 300, upper left contact of cam 323, upper left contact of cam 318, left front contact of relay 305, to ground at the right contact of cam 312.
- In position 4, magnet 317 is again operated, to control the group selecting operation of the selector. The intermittent shunt for the stepping relay extends at this time from ground over the lower contact of cam 303, brush 324, commutator strip 325 and the upper right contact of cam 306. Relay 305 releases when the fundamental circuit is opened by the completion of the selection, releasing magnet 317. As before it advances sequence switch 300, this time to position 5.
- In position 5, relay 305 is again operated and locked, advancing sequence switch 300 to position 6. In position 6 the low speed up-drive magnet 326 is operated, the circuit extending over the lower right contact of cam 323 and from thence over the same circuit as traced for high speed magnet 317. The final selector is now elevated more slowly to select the line designated by the wanted number. The shunting circuit for the stepping magnet in position 6 is the same as traced in position 2.
- Since the wanted number represents a private branch exchange, the selector will be brought to rest, following units selection, on the first of a group of trunks leading to the exchange. The release of relay 305 advances the sequence switch to position 8. When sequence switch 300 leaves position $7\frac{1}{4}$ the holding circuit of relay 301 is opened, initiating certain operations which will be described hereinafter.
- When sequence switch 300 reaches position $7\frac{3}{4}$, relay 305 is operated in a circuit from battery, through the left winding of relay 305, left contact of cam 327, inner front contact of relay 310 to ground. When the sequence switch reaches position 8 with relay 305 operated, the condition of the line is tested by means of a circuit extending from ground, lower left contact of cam 328, winding of relay 313, winding of relay 329, upper contacts of cam 330, right front contact of relay 305, left contacts of cam 309 over sleeve conductor 331, brush 332, to the sleeve terminal of the first trunk of the group. Assuming that this trunk is busy, battery will be connected to the sleeve terminal as will be described hereinafter. Likewise, due to the low resistance marking the sleeve of P. B. X. trunks other than the last, the potential on the sleeve terminal will cause the operation of relay 329 but not of relay 313. Relay 329 closes a holding circuit for relay 305 extending from battery, lower left and upper right contacts of cam 304, right winding of relay 305, lower left contact of cam 306, upper left contact of cam 307, to ground at the front contact of relay 329. Relay 305 advances the sequence switch to position 9, where the holding circuit is maintained. In this position magnet 326 is again energized to cause the selector to hunt for an idle trunk. When one is found, relay 329 releases, in turn releasing relay 305 and magnet 326 to bring the selector to rest. Relay 305 is maintained energized between trunk terminals and the brushes are properly centered by means of a circuit extending from battery through the left winding of relay 305, right contact of cam 335, right winding of relay 310, commutator strip 336, brush 337, upper right contact of cam 323, upper left contact of cam 318, left front contact of relay 305, upper contact of cam 312, inner front contact of relay 310 to ground.
- As soon as relay 305 releases, a circuit is closed from battery, left contacts of cam 304, resistance 338, upper left contact of cam 339, right back contact of relay 305, left contacts of cam 309, sleeve conductor 331, brush 332, conductor 501, right back contact of relay 502, windings of relay 503 to ground. Relay 503 operates, closing an obvious circuit for relay 504. Relay 504 connects shunted battery to the sleeve of calling jack 505 to mark the intercepting line terminating in that jack as busy. Relays 503 and 504 also prepare circuits which will be traced as they become effective.
- The release of relay 305 also closes a circuit from battery, through the winding of sequence switch magnet 300, lower contact of cam 321, left back contact of relay 305, upper contact of cam 312, inner front contact of relay 310 to ground. Sequence switch 300 advances to position 12 in this circuit. As the sequence switch passes through position 10, the holding circuit of relay 310 is extended over the upper left contact of cam 311.

directly to the outer front contact of that relay, rendering the continued energization of the relay independent of relay 313. The sequence switch is then advanced to position 5 13 by means of a circuit over the right contacts of cam 316 to ground at the inner front contact of relay 310, and to position 14 in a circuit over the lower contact of cam 321, left back contact of relay 305 to ground at 10 the right contact of cam 312. In position 14, tip conductor 308 is connected over the lower contacts of cam 307 to brush 334 and conductor 506 of the intercepting line circuit, while ring conductor 301 is connected over 15 the upper contacts of cam 340 to brush 333 and conductor 507 of the intercepting line circuit.

It will be remembered that when sequence switch 300 left position 7 1/4, relay 201 was released. The release of relay 201 advances sequence switch 200 to position 9. In position 9 battery through the left winding of relay 201 is connected over the upper left contact of cam 211, and the left contact of 25 cam 210 to tip conductor 205, and ground is connected over the left contacts of cam 216, upper left contact of cam 202 and the upper left contact of cam 203 to ring conductor 204. This reverses the direction of current flow 30 over the fundamental circuit to the sender, advancing the sender to a position where it connects ground to conductor 120, operating relay 119 which thereupon locks through both windings to ground at the outer contact of 35 relay 118. The sender then releases.

Relay 201 operates in this circuit, advancing sequence switch 200. In position 10 the right winding of relay 201 is connected to the tip conductor, in parallel with the left 40 winding, over the upper contact of cam 219, upper right and lower left contacts of cam 230, upper left winding of repeating coil 231, and the upper right and lower left contacts of cam 206. When sequence switch 200 leaves position 10, relay 201 releases, stopping the sequence switch in position 11.

Assuming that the operator has inserted plug 116 in jack 115, a circuit is now closed from battery, lower right winding of repeating coil 109, winding of relay 122, lower normal contact of ringing key 121, rings of plug 50 116 and jack 115, inner contact of relay 119, ring conductor 204 of trunk 114, upper left and lower right contacts of cam 203, lower 55 left winding of repeating coil 231, both windings of relay 232, upper left winding of repeating coil 231, upper right and lower left contacts of cam 206, tip conductor 205, outer contact of relay 119, tips of jack 115 60 and plug 116, upper normal contact of ringing key 121, upper right winding of repeating coil 109 to ground. Relay 232 operates closing an obvious circuit for relay 233 which locks over its left contact to cam 234. Relay 233 closes a circuit from ground at its 65 right contact, upper contact of cam 210, upper left contact of cam 211, left winding of relay 201 to battery. Relay 201 operates, advancing sequence switch 200 to position 12. Relay 201 is held operated in a circuit from 70 battery through its left winding, right contact of cam 207, left front contact of relay 201, left contacts of cam 216 to ground, until the sequence switch leaves position 11 1/4 to prevent the premature operation of relay 220. 75

When sequence switch 200 reaches position 12, a circuit is closed from battery, through the winding of relay 220, right contact of cam 235, left normal contact of relay 220, upper left and lower right contacts of cam 230, left back contact of relay 201, lower contacts of cam 243 to ground. Relay 220 operates closing a holding circuit for itself over the right contact of cam 235, left alternate contact of relay 220, left contact of cam 236, back contact of relay 237, to ground at the right contact of relay 233. Relay 220 also closes a circuit from battery through the winding of magnet 200, lower contact of cam 219, right alternate contact of relay 220, 80 left contact of cam 243 to ground, advancing the sequence switch to position 13. In position 13 ringing current is applied to the called line. The circuit for it may be traced from ringing source 238, contact of cam 239, 85 winding of relay 237, outer right front contact of relay 220, right contact of cam 228, brush 223, conductor 301, upper contacts of cam 340, brush 333, conductor 507, lower winding of alternating current relay 508, 90 condenser 509, conductor 506, brush 334, lower contacts of cam 307, conductor 308, brush 222, lower contact of cam 229 to ground.

Relay 508 operates, locking in a circuit from battery through its upper winding and 105 inner front contact to ground at the outer front contact of relay 504. Relay 508 also closes a circuit from ground at its upper front contact, through the winding of relay 510 to battery and, in parallel therewith, 110 through the lower winding of relay 511 to battery. Relays 510 and 511 operate. Relay 511 closes a circuit from battery, over the back contact of relay 512, lower front contact of relay 511, through lamp 513 to 115 ground. The lighting of lamp 513 informs the A operator at whose position this line appears, that a call has been extended thereto.

The operator thereupon inserts answering 120 plug 400 of a cord circuit at her position into the intercepting jack 514 of this line. A circuit is closed from battery through the winding of relay 401, sleeves of plug 400 and jack 514, winding of relay 512 to ground. Relays 125 401 and 512 operate in this circuit. The operation of relay 401 closes an obvious circuit for lighting the answering cord lamp 405, but lamp 405 is shunted as subsequently described. Relay 512 is operating discon- 130

- 6 nects battery from lamp 513 and connects it over the lower front contact of relay 512 and the lower back contact of relay 515 to lamp 516 and ground. Relay 512 also closes an 5 obvious circuit for relay 502. Relay 502 opens the circuit of relay 503 and therefore of relay 504. It also opens the locking circuit of relay 508 which releases relays 510 and 511. Relay 502 connects a shunted battery over its inner front contacts to sleeve conductor 501 as a busy condition. It also connects battery through resistance 517, to ring conductor 507 during the releasing time of relay 510. When relay 511 closes its back 10 contact, it completes a circuit from battery through the lower left winding of repeating coil 406, winding of supervisory relay 407, lower normal contact of ring-back key 408, ring conductor 409, rings of plug 400 and 15 jack 514, back contact of relay 511, upper back contact of relay 515, retard coil 519, tips of jack 514 and plug 400, tip conductor 410, upper normal contact of key 408, front contact of relay 401, upper left winding of 20 repeating coil 406 to ground. Relay 407 in operating closes a circuit from battery through the left winding of relay 411, normal contact of relay 412, right normal contact of relay 413, front contact of relay 407, 25 left normal contact of relay 413, resistances 414 and 415 to ground at the right contact of relay 401. This circuit shunts lamp 405 preventing its lighting. Relay 411 operates but is immediately released by the operation of 30 the listening key.
- The connection of battery to conductor 507 as above described causes the operation of relay 237 which opens the holding circuit of relay 220, disconnecting ringing current 35 from the line. With relay 220 released, a circuit is closed from battery through the right winding of relay 201, upper contact of cam 219, right normal contact of relay 220, upper left and lower right contacts of cam 40 45 221 to ground. Relay 201 energizes and advances sequence switch 220 to position 14 whereupon it releases to advance the sequence switch to position 15. In position 15 relay 201 is reoperated in a circuit from battery through its left winding, left contacts of cam 211 to ground, advancing sequence switch 200 to position 16 which is the talking position. Relay 201 is held operated in positions 15 to 17 inclusive under the control 50 55 of the operator at the calling office, the circuit extending from battery through its left winding, upper left contact of cam 211, upper contact of cam 210, to ground at the right contact of relay 233.
- 60 As soon as the operator at the called office has inserted plug 400 in jack 514 she will operate listening key 416 and insert plug 402 in jack 505. The operation of the key 416 connects her telephone circuit with the cord 65 circuit and also closes a circuit from ground

over its lower contact, right winding of relay 413 to battery. Relay 413 operates and locks in a circuit from battery over its right alternate contact, front contact of relay 407, left alternate contact and left winding of relay 413, resistance 415 to ground at the right front contact of relay 401. The operation of relay 413 disconnects relay 411 but maintains the shunt around lamp 405.

The insertion of plug 402 in jack 505 completes a circuit from battery, through the windings of relays 403 and 404, sleeves of plug 402 and jack 505, left back contact of relay 504, winding of relay 518 to ground. Relays 403, 404 and 518 operate. The operation of relay 403 disconnects relay 417 from and connects relay 418 to the repeating coil 406. Relay 404 in operating closes an obvious circuit for relay 419 which opens the busy test circuit and completes the circuit of relay 418. This circuit extends from battery through the left winding of relay 418, outer front contact of relay 403, lower right winding of repeating coil 406, lower normal contact of ringing key 420, lower normal contact of dialing key 421, rings of plug 402 and jack 505, lower left winding of repeating coil 520, back contacts of relay 521, through direct current relay 522 in parallel with alternating current relay 523 and condenser 524, upper left winding of repeating coil 520, tips of jack 505 and plug 402, outer front contact of relay 419, upper normal contacts of keys 421 and 420, upper right winding of repeating coil 406, inner front contact of relay 403, right winding of relay 418 to ground. Relays 418 and 522 operate, relay 418 opening the circuit of lamp 422 and relay 522 opening the locking circuit of relay 525.

The A operator now operates ringing key 420 which applies ringing current to relay 523 over a portion of the circuit above traced. Relay 523 operates closing an obvious circuit for relay 526. Relay 526 causes the application of ringing current to the trunk 534 leading to the private branch exchange from source 527, through lamp 528, outer lower contact of relay 526 to the branch exchange and back over the upper front contact of relay 526 to ground. At the same time, ringing tone is returned to the calling subscriber over the inner lower contact of relay 526, condenser 529 and the ring conductor 507.

When the operator at the branch exchange answers which she does orally during an interval between ringing, the A operator may reply. She will then operate key 537. The operation of this key closes an obvious circuit for relay 515 which then locks over its outer upper front contact to ground at the outer upper contact of relay 512. With relay 515 operated, lamp 516 is extinguished, the circuit of supervisory relay 240 is

closed and a new circuit closed for relay 407. The new circuit of relay 407 may be traced from ground through the upper right winding of repeating coil 231, upper left contact of cam 229, brush 222, conductor 308, lower contacts of cam 307, brush 334, conductor 506, inner upper front contact of relay 515, resistance 539, lower back contact of relay 511, rings of jack 514 and plug 400, conductor 409, lower normal contact of key 408, winding of relay 407, lower left winding of repeating coil 406 to battery. The circuit of relay 240 may be traced from battery, through the lower right winding 10 of repeating coil 231, winding of relay 240, lower right contact of cam 228, brush 223, conductor 301, upper contacts of cam 340, brush 333, conductor 507, back contact of relay 510, resistance 538, lower front contact of relay 515, tips of jack 514 and plug 400, conductor 410, upper normal contact of key 408, left front contact of relay 401, upper left winding of repeating coil 406 to ground. Relay 240 operates in this circuit, closing at its front contact a shunt around the high resistance winding of relay 232. This reduces the resistance in the circuit of relay 122 sufficiently to permit that relay to operate. The operation of relay 122 connects battery through resistance 123 in shunt of lamp 117, extinguishing that lamp to inform the key indicator operator that the connection has been extended to the distant exchange. Conversation may now proceed 30 between the subscriber at substation 100 and the operator at the branch exchange, who will complete the connection to the wanted person.

It may be noted that a talking circuit 40 exists between the "A" operator and the calling subscriber, before key 537 is operated, which extends through condensers 540 and 541 by means of which the operator may talk with the calling subscriber if necessary, without charging the call.

Owing to the length of the line between the central office and the branch exchange, ringing current is transmitted from the branch office as a disconnect signal. This 50 current operates relay 530, which closes a circuit from battery through the winding of relay 531, front contact of relay 530 to ground at the inner upper back contact of relay 526. Relay 531 closes a circuit from battery through the winding of relay 532, back contact of relay 533, front contact of relay 531 to ground at the inner upper back contact of relay 526. The operation of relay 532 closes a circuit from battery through 60 the winding of relay 533, front contact of relay 532, front contact of relay 531 to ground at the inner upper back contact of relay 526. Relay 533 is slow to operate, but on completely attracting its armature it 65 opens the circuit of relay 532, which, being

slow to release, closes its back contact after an interval. A circuit is now closed from battery, through the winding of relay 521, inner right front contact of relay 518, back contact of relay 532, front contact of relay 70 533, front contact of relay 531 to ground at the inner upper back contact of relay 526.

Relay 521 locks over its front contact, inner left contact of relay 518 to ground at the inner upper back contact of relay 75 526. The operation of relay 521 opens the circuit of relay 418, thereby closing a circuit from battery through lamp 422, resistance 423, back contact of relays 418 and 417, inner front contact of relay 419 to 80 ground, lighting lamp 422 as a disconnect signal to the "A" operator. It is apparent from the foregoing that the ringing current must be applied for a definite interval in order that the "A" operator may receive a 85 disconnect signal. This delay prevents the premature display of such a signal from momentary disturbances of the line.

When the "A" operator sees lamp 422, she withdraws plugs 402 and 400 from jacks 90 505 and 514 respectively. The removal of plug 402 releases relays 419 and 518 extinguishing lamp 422. With relay 518 released, relay 521 also releases. The removal of plug 400 releases relay 512, opening the circuits of relays 502 and 515. Relay 502 removes the busy condition from conductor 501 and reconnects relay 503 thereto, reoperating relay 504 to mark the sleeve of jack 505 busy. The removal of plug 400 also 100 releases relays 401, 407 and 413 restoring the "A" operator's cord to normal.

The release of relay 515 opens the circuit of supervisory relay 240, which releases, opening the shunt around the high resistance 105 winding of relay 232. This increase in resistance releases relay 122 which opens the shunt around lamp 117, permitting it to relight. The key indicator operator will thereupon remove plugs 116 and 104 from 110 the jacks 115 and 106, restoring her cord circuit to normal.

The removal of plug 116 opens the circuit of relay 232 which releases in turn releasing relays 233 and 201. Relay 201 on 115 releasing advances sequence switch 200 to position 18. As the sequence switch leaves position 16½ ground is disconnected from sleeve brush 224. When the sequence switch arrives in position 18, the down drive magnet is energized in a circuit extending from battery through the winding of magnet 241, lower right and upper left contacts of cam 202, left contacts of cam 216 to ground. The selector is restored to normal under the control of magnet 241. When it reaches normal, a circuit is closed from battery through the winding of sequence switch magnet 200, lower left contact of cam 208, normal commutator segment 242, brush 217, upper right 130

- and lower left contacts of cam 212 to ground. Sequence switch 200 advances to position 1 in this circuit restoring the incoming selector circuit completely to normal.
- 5 The removal of ground from brush 224 opens the holding circuit of relay 310 which releases. The release of relay 310 closes a circuit from battery, through the winding of sequence switch magnet 300, lower right and 10 upper left contacts of cam 316, inner back contact of relay 310 to ground, advancing the sequence switch to position 15. Relay 310 is reoperated in position 15 in a circuit from battery, upper contact of interrupter 15 341, upper contact of cam 335, right winding of relay 310, left contacts of cam 314 to ground. The operation of relay 310 closes the same circuit for magnet 300 as was traced in position 1, advancing the sequence switch 20 to position 16. Relay 310 is again operated in position 16 over the lower contact of interrupter 341 and the lower left contact of cam 335 to advance sequence switch 300 to position 17. Sequence switch 300 is moved to 25 position 18 in a circuit over the lower right and upper left contacts of cam 316 to ground at the inner back contact of relay 310, which released as soon as the switch left position 16. In position 18 the final selector is 30 restored to normal under the control of down drive magnet 342 which is energized in a circuit from battery through its winding, lower left contact of cam 318, upper right contact of cam 323, lower contact of cam 35 303 to ground. When the selector switch reaches normal, a circuit is closed from battery through the winding of magnet 300, right contact of cam 321, normal commutator segment 343, brush 324, lower contact 40 of cam 303 to ground, advancing the sequence switch to position 1 where the selector circuits are normal.

When sequence switch 300 leaves position 16, battery is disconnected from sleeve brush 45 332, releasing relay 503 and in turn relay 504. Relay 504 in releasing removes the busy condition from jack 505.

Connection initiated at branch exchange.

- 50 When a subscriber at the branch exchange wishes to talk to a subscriber at the main exchange or at some other exchange, an impulse of ringing current will be transmitted from the branch over the trunk 534 of the 55 necessary duration. In consequence relays 530, 531, 532 and 533 will be successively operated and relay 532 released as above described. When relay 532 closes its back contact, a circuit is completed from battery, 60 through the winding of relay 525, back contacts of relays 518 and 532, front contacts of relays 533 and 531, to ground at the inner upper back contact of relay 526. Relay 525 operates and locks over its inner right contact to ground at the back contact of relay 65 522. It closes a circuit from battery over the back contact of relay 503, left contact of relay 525, line lamp 535 to ground, lighting the lamp. Relay 525, also closes a circuit from battery through the winding of relay 502, outer right contact of relay 525 to ground at the right back contact of relay 504. Relay 502 connects the busy condition to sleeve conductor 501 to mark the line busy to final selectors. The operator now inserts 70 answering plug 400 of a cord circuit in jack 505. A circuit is completed from ground through relay 518, left back contact of relay 504, sleeves of jack 505 and plug 400, winding of relay 401 to battery. Relay 401 connects ground to lamp 405 and completes the tip conductor of the cord circuit. However, a circuit is at once closed from battery, through the lower left winding of repeating coil 406, winding of relay 407, lower normal 75 contact of key 408, conductor 409, rings of plug 400 and jack 505, lower left winding of repeating coil 520, back contacts of relay 521 through relay 522 and relay 523 in parallel, upper left winding of coil 520, tips of jack 505 and plug 400, upper normal contact of key 408, left contact of relay 401, upper left winding of coil 406 to ground, operating relays 522 and 407. Relay 407 80 closes the circuit previously traced for relay 411, but as the operator immediately operates talking key 416, relay 413 is operated and locked as before, holding lamp 405 extinguished.
- The operation of relay 518 opens the energizing circuit for relay 525, and closes a new circuit for relay 502. The operation of relay 522 opens the locking circuit of relay 525, extinguishing line lamp 535. 85
- The operator now ascertains from the calling subscriber the number of the wanted subscriber and extends a connection thereto by the use of calling plug 402; and in the case of a local subscriber by the use of dial 424. If the subscriber at the branch exchange wishes to recall the "A" operator, she will cause the reapplication of ringing current to the trunk 534, operating relays 530, 531, 532 and 533 as before. Relay 518 being operated at this time, relay 521 will 90 100 operate as in the case of the disconnect signal. However, since plug 400 is inserted in jack 505, the operation of relay 521 releases relay 407 in turn releasing relay 413 and lighting lamp 405. The release of relay 413 permits relay 411 to operate. When interrupter 425 closes its contact a circuit is completed thereover from ground over the front contact of relay 411, winding of relay 412 and battery. While relay 412 is operated, relay 411 is held operated through its two windings in series by way of the right front contact of relay 412. Relay 412 also 105 closes a circuit from battery over its left contact through buzzer 426 to ground giving 110 115 120 125 130

- the operator an audible signal. As soon as the operator responds to this signal by operating listening key 416, relay 413 operates to open the circuit of relay 411, silencing 5 the buzzer. In order to reoperate relay 522 and extinguish lamp 535, the "A" operator may either operate her ringing key 420 or withdraw and reinsert plug 400 in jack 505. Ringing current will operate relays 523 and 5 10 526, opening the locking circuit of relay 521 at the contact of relay 526, while withdrawing plug 400, releases relay 518 momentarily to unlock relay 521 at the contact of relay 518.
- 15 If the subscriber at the branch exchange should attempt a connection over a trunk after it has been seized by a calling final selector a special signal is given to the "A" operator. It will be remembered that the 20 seizure of the line by the final selector operates relays 503 and 504, while the application of ringing current from the incoming selector operates relays 508, 510 and 511, lighting lamp 513. The application of ringing current to trunk 534 will operate relays 530, 25 531, 532 and 533, and release relay 532 as previously described. Since relay 518 has not been operated the release of relay 532 causes the operation of relay 525. With relays 503 and 525 operated, a circuit is closed from battery, over interrupter 536, right front contact of relay 503, left front contact of relay 525 to ground through lamp 535, causing this lamp to flash, giving a distinctive signal to the "A" operator. The operator will then insert plug 400 of one of her cords into jack 505. This causes the 30 operation of relay 522, releasing relay 525 and extinguishing lamp 535. She will then 35 inform the subscriber that the trunk has been seized for an incoming call, after which she will withdraw plug 400 and complete the incoming connection in the manner described.
- 40 If the key indicator operator wishes to recall the "A" operator she may operate the 45 ringing key 121 of her cord circuit. Relays 232 and 233 being slow to release do not release the incoming circuit during brief interruptions of the trunk. The ringing current is repeated through coil 231 to relay 508 which operates. If key 537 has not yet 50 been operated, relays 510 and 511 will operate, relay 511 locking in a circuit from battery, through its upper winding and contact, inner upper contact of relay 512, outer 55 left contact of relay 518 to ground at the inner upper back contact of relay 526. Relay 511 will open the bridge through retard coil 538, thereby releasing relay 407, permitting lamp 405 to light. Relays 508 and 510 60 release when ringing ceases. When the "A" operator rings the branch exchange, relays 524 and 526 will be operated as described and relay 511 will be released, reoperating 65 relay 407 to extinguish lamp 405. She will then reoperate her listening key until the branch operator answers. If relay 515 has been operated at the time of the re-ring, the talking circuit will have been completed, so that the operation of relay 511 disconnects 70 the ring of jack 514 from conductor 506, thus opening the circuit of relay 407 to light lamp 405.
- What is claimed is:
1. In a telephone exchange system, a machine switching office, an operator's position thereat, a two-way line extending from a remote point and terminating at said operator's position, intercepting terminals individual to said line appearing in the banks of selector switches, means for extending a connection to said line comprising means for causing a selector switch to connect with said switch terminals, and means at said operator's position for connecting said terminals with said line. 75 80 85
2. In a telephone exchange system, a machine switching office, an operator's position thereat, a two-way line extending from a remote point and terminating in a jack at said operator's position, an intercepting line individual to said first line extending from selector switch banks and terminating in a jack at said operator's position, and means for extending the connection to said line comprising means for causing a selector switch to connect with said intercepting line and a cord circuit at said operator's position for connecting said jacks together. 90 95
3. In a telephone exchange system, an office, a two-way line extending from a remote point and terminating in said office, a signal at said office associated with said line, intercepting terminals for said line, means for extending a connection to said intercepting terminals, means at said office for connecting said intercepting terminals to said line, means to operate said signal in one manner when a call is initiated at said remote point and said terminals are free, and means for operating said signal in a distinctive manner when a call is initiated at said remote point if, at the time, said intercepting terminals have been seized by said connection extending means. 100 105 110 115
4. In a telephone exchange system, a machine switching office, an operator's position thereat, a two-way line extending from a remote point and terminating at said operator's position, a signal at said position associated with said line, intercepting terminals for said line appearing in the banks of selector switches, means at said operator's position for connecting said terminals to said line, means to operate said signal in one manner when a call is initiated at said remote point and said terminals are free, and means for operating said signal in a distinctive manner when a call is initiated at said remote point if, at the time, said in- 120 125 130

- tercepting terminals have been seized by a selector switch.
5. In a telephone exchange system, a machine switching office, an operator's position 5 thereat, a two-way line extending from a remote point and terminating in a jack at said operator's position, a lamp signal associated with said jack, an intercepting line individual to said first line extending from 10 selector banks and terminating in a jack at said operator's position, a cord circuit at said operator's position for connecting said lines, means to operate said signal in one manner when a call is initiated at said remote point 15 and said intercepting line is free, and means for operating said signal in a distinctive manner when a call is initiated at said remote point if, at the time, said intercepting line has been seized at said selector bank.
- 20 6. In a telephone exchange system, an office, an operator's position thereat, a two-way line extending from a remote point and terminating at said operator's position, intercepting terminals for said line, means 25 for extending a connection to said terminals, a link circuit at said position for connecting said terminals to said line, a signal in said link circuit responsive to ringing current applied over said connection extending 30 means, and means for maintaining said signal until ringing current is applied to said line.
7. In a telephone exchange system, an
- office, an operator's position thereat, a two-way line extending from a remote point and terminating at said operator's position, intercepting terminals for said line, means for extending a connection to said terminals, a link circuit at said position for connecting said terminals to said line, a signal in said link circuit responsive to ringing current applied over said connection extending 35 means, a ringing key for applying ringing current to said line, and means for maintaining said signal until said key has been 40 operated.
8. In a telephone exchange system, an office, an operator's position thereat, a two-way line extending from a remote point and terminating at said operator's position, intercepting terminals for said line, means for extending a connection to said terminals, 45 a link circuit at said position for connecting said intercepting terminals to said line, a relay associated with said terminals responsive to ringing current applied over said connecting means, a ringing signal in said link circuit responsive to said relay, a ringing relay in said line, a ringing key in said link circuit for controlling said ringing relay 50 and a locking circuit for said first relay under the control of said ringing relay.

In witness whereof, I hereunto subscribe my name this 3rd day of February, A. D., 1927.

WILLIAM C. JORDAN.
